UNITED STATES PATENT OFFICE.

ADELBERT AMES, JR., OF TEWKESBURY, MASSACHUSETTS.

REFLECTOR.

1,280,626.

Specification of Letters Patent.

Patented Oct. 8, 1918.

Application filed January 17, 1916. Serial No. 72,504.

To all whom it may concern:

Be it known that I, ADELBERT AMES, Jr., a citizen of the United States, residing at Tewkesbury, in the county of Middlesex 5 and State of Massachusetts, have invented certain new and useful Improvements in Reflectors, of which the following is a specification; reference being had therein to the accompanying drawings.

10 My invention relates to lights and lighting wherever control of radiant illumination is desired, and pertains particularly to headlights such as are used on automobiles, interurban cars, and other vehicles.

15 The discomfort and danger caused to users of the highway by the use at night of ordinary headlights on vehicles is well known. There is also a considerable inconvenience and danger to the driver of the

20 vehicle.

The rays from a light source placed at the focus of the commonly used parabolic reflector go out in a bundle of parallel rays and light up the distant road, without lighting up, however, the road in the near or middle distance. It is a common practice 25 of the users of such headlights to obtain illumination of the nearer parts of the road by putting the light source out of focus, either in front or behind, and thus change the reflected rays from a narrow parallel bundle to a broad diverging one. If the light source is put behind the focus, this effect is produced by the rays striking the 30 reflector at such an angle that they flare out directly. If the light source is put in front of the focus the rays strike the reflector at such an angle that they are reflected back across each other, and then flare out. The

35 disadvantage of using such a diverging beam of light is: 1st. That the distant road is not properly illuminated and fast driving is very dangerous. 2nd. Part of the diverging bundle of rays radiate upward and are blinding to the other users of the highway, and are wasted for roadway illuminating purposes. If the light is put in the focus, and the distant road illuminated, danger arises owing to the fact

40 that the driver cannot see the near road.

To meet these difficulties numerous States have passed laws requiring that the illumination from headlights shall radiate the light of the road in a predetermined manner.

The object of the invention is to provide

a headlight which will do away with the above-mentioned dangers and nuisances, utilize all of the radiant light energy and meet the different laws of the different 60 States; for example, a headlight, 1st, which will light up the road at a distance as far as possible ahead of the car. 2nd, which will light up all the road and sides of the road between such a distant point 65 and a point a few feet ahead of the car. 3rd, which will light up said road and sides of road to any extent and intensity that may be required. 4th, To accomplish the foregoing purposes in such a manner 70 that no glare or blinding effect is caused to approaching pedestrians or drivers, or other users of the highway. 5th, To conserve and utilize all of the radiant light energy of the lamp.

75 I accomplish these results by means of a reflector formed by the revolution of a suitable conic section as a parabola or distantly focused ellipse; in fact any suitable concave reflector, a source of light, both in 80 and out of the focus of the reflector, and suitable means as reflectors, screens, and the like, for controlling the rays from said sources; said elements being hereinafter shown, in various forms, and as bearing 85 various relations to each other, but bound together upon certain general principles, the embodiment of which I desire to protect in the broadest manner legally possible.

In the drawings illustrating the principles 90 of my invention, and the best mode now known to me of embodying them in operative structures,

Figure 1 is a diagrammatic elevation of a parabolic reflector combined with separate 95 light sources, one at the focus, and the other to the rear, and a shade to absorb light that would otherwise be reflected by a portion of the reflector.

Fig. 2 is a front view of the shade shown 100 in Fig. 1.

Fig. 3 is an elevation showing a continuous light source, a part of which only, is at the focus, and a shade to absorb undesired rays after reflection.

Fig. 4 shows separate light sources, one at the focus and the other in front of it, with shade and auxiliary reflector.

Fig. 5 is a front view of shade and reflector shown in Fig. 4.

Fig. 6 is a view like Fig. 4, except the second source of light is at the rear of

the focus and the shade and reflector are above the sources of light.

Fig. 7 is a front view of the shade and reflector appearing in Fig. 6.

5 Fig. 8 shows a cylindrical electric light bulb having its sources of light like those in Fig. 6, combined with a reflector and shade above the light source so arranged as to allow light from the source at the focus 10 and strike both halves of the parabolic reflector.

Figs. 9 and 10 are front views of the reflector and the shade shown in Fig. 8.

15 Fig. 11 is a diagrammatic view to illustrate why a source of light such as is obtainable placed at the focus of the reflector, will not give a bundle of parallel rays.

20 Fig. 12 is a diagrammatic view of a parabolic reflector, having a cylindrical light bulb, and reflector, below its axis; one of its light sources being at the focus and the other in front of it.

25 Fig. 13 illustrates a particular form of light bulb, and the astigmatic effect of a semi-cylindrical mirror, adapted to be used with a parabolic mirror.

30 Fig. 14 is like Fig. 1, with the exception that it shows a mirror in the place of the shade, and the light source in focus slightly drawn back.

35 Fig. 15 shows a parabolic reflector, a continuous source of light in a plane perpendicular to the axis of the mirror, and passing through the focus; the edge of the reflector being determined by said plane.

40 Fig. 16 is a view similar to Fig. 15; the plane passing through the focus of the reflector and containing the sources of light, being at an angle to the axis of the reflector.

45 I will now describe some of the various forms of structure embodying my invention.

An electric light 1, Fig. 1, having two sources which are inclosed in a spherical bulb 2, is mounted at the apex of a parabolic reflector 3, so that one source of light 4 is at the focus indicated by plane f , of the reflector, and the other in rear of the focus, at 5. A small screen 6 lies above the sources of light. Such a structure prevents all radia-

50 tion of light from either source being reflected by the upper half of the reflector. Rays 7 from the source 4 at the focus are deflected outwardly in a parallel bundle that lights up the distant road without rising

55 above the level of the top of the reflector; the lamp being assumed to be mounted with the axis 8-8 of the reflector in a horizontal plane. But rays 9 from the source 5 inside

60 of the focus, and radiating downwardly, will, after striking only the lower half of the parabolic reflector, be deflected downwardly and outwardly, and will light all the space between the bundle of parallel rays

65 and a point a few feet in front of the car, as is shown.

The rays 9' from 5 radiating upwardly which would have been reflected upwardly by the upper half of the reflector, are prevented from striking said reflector, by the screen 6.

70 The means for preventing the upward reflection of the upwardly radiating rays 9' from the sources out of focus, as at 5, may be varied. It may either be a screen placed between the said sources and the reflector, as just described, or it may be a device placed in the path of said rays 9' from source as 5', Fig. 3, after reflection, as a screen 10.

75 The prevention of the reflection in an undesirable direction, of the rays from the source not in focus, can be accomplished by the proper placing of that source and the large reflector relative to each other.

80 If the reflector 3', Fig. 15, does not extend beyond a plane 14, passing through the focus f , and the light sources not in focus, are placed in that plane, as at 15, all rays 16 from 15, striking the reflector, will be reflected in the same direction relative to the 85 axis 8 of the reflector, in this case downwardly. For the rays from 15 will strike the upper half of the reflector as if they came from 17, in front of the focus f , and the lower half as if they came from 18, behind the focus. Although in Fig. 15, the plane 14, passing through the focus, is shown perpendicular to the axis 8, it may, if desired, be at an angle with the axis; and, if the reflector 3'', Fig. 16, does not extend 90 beyond such plane 14' and all of the light sources 15' are situated in it, the resultant effect will be the same.

95 The light source 19, Fig. 4, not in focus, may be placed in front of the focus f , and 105 when such is the case, a screen 20 is placed below it, as shown, which prevents the rays from both sources striking the lower half of the parabolic reflector; the rays 21 from the source 19, outside the focus f , strike only 110 the upper half of the reflector, and being deflected downwardly and outwardly, illuminate the road in the same way as just described.

115 In neither case will rays be deflected above the parallel bundle of rays 22 coming from the source of light 4 situated at the focus of the reflector.

120 This arrangement can be improved upon, by making the inner face of the screen a properly shaped reflecting surface, for example, 6, Fig. 1, and 6', Fig. 6. The upwardly radiating rays 22', Fig. 6, instead of being absorbed, are reflected back to the lower half of the parabolic reflector as if they 125 had come from points 23', Fig. 6, inside the focus, and are by it reflected downwardly and outwardly. The intensity of the illumination is of course thus greatly increased.

130 A reflecting screen of any suitable shape

can be used, cylindrical, conical, spherical, elliptical, plain, etc., providing it is so placed that it reflects all the rays from one or both sources, as the case may be, to one side or the other of the focus as is desired.

For some purposes, this arrangement may be bettered by using a smaller screen 25, Fig. 8, and 25', Fig. 12, close to the lamp 26, 26', as is respectively shown in Figs. 8 and 12.

10 The advantage of this arrangement is, that it allows a larger percentage of rays, from the light source 4 at the focus, to strike both halves of, and almost the entire surface of the parabolic reflector 3 (see rays 27, 28, 29, 30, Fig. 8, 31, 32, 33, 34, Fig. 12) and be projected outwardly with but one reflection.

15 The nearer the small screen can be placed to the second light source, the more rays from the source at the focus, will strike the parabolic reflector, at the same time preventing rays from source not in focus, from being reflected from any part of the parabolic reflector except that desired. But to get the small screen as near as possible to the second light source, the bulb of that part of the 20 light must be cylindrical and as small in diameter as possible. On the other hand, the larger the space around the light source in an incandescent bulb, the longer the lamp will last, and the more slowly will the bulb blacken. To gain this space, the shape of the bulb beyond the point where it is necessary to place the small screen, may be changed from cylindrical to spherical, as clearly appears in Fig. 13.

25 The arrangement that allows the larger percentage of the rays from the light source at the focus, to be projected outwardly with but one reflection, makes a somewhat more efficient light than that in Fig. 14. From 5% to 40% of the incident light is absorbed by reflecting surfaces, and there is therefore, some loss in the double reflection of such rays, 22', Fig. 14. The arrangement in Fig. 14, however, has an advantage over the arrangement in Fig. 8 in that with proper focusing of the light, no rays will be projected above the axis of the reflector, while with the arrangement in Fig. 8, no matter 30 how the light is focused, there will be considerable upwardly diverging rays.

35 The reason for this is, that the most concentrated light sources are not points, but are of considerable size. As a result, although put exactly at the focus of a parabolic reflector, certain rays will not go out in a parallel bundle, but will diverge upwardly and downwardly. For example, in Fig. 11, rays 40 from points 41 on the light source 60 which strike the reflector as if they had come from points 4' outside of the focus f , will follow the directions 41, 42, 40, both above and below the axis, and after crossing the axis of the reflector at some distance in 65 front, will diverge downwardly and up-

wardly. Rays 43, from 44 of the source, will strike the reflector as if they had come from behind the focus, and will flare upwardly and downwardly. This cannot be remedied by changing the light source relative to the 70 focus, for if it is drawn back so that rays 40 from 41 strike reflector as if they had come from the focus, points 44 will be more displaced than before, and rays 43 from them, will flare out more broadly. If, however, a screen or a screen reflector, in this case a hemisphere having its center back of the focus, is placed to properly prevent light from both sources striking one side of the parabolic reflector as in Fig. 14, the light 75 source 4 can be moved relatively to the focus f (in this case back) so that no rays will strike the parabolic reflector as if they came from points in front of the focus, and the resulting reflected beam will be composed of 80 entirely parallel or downwardly deflecting rays; such an arrangement has the advantage of allowing the greatest elevation of the beam, and, therefore, the greatest amount of distant illumination with the least amount 85 of glare.

While any shaped reflecting screen that complies with the requirements already mentioned, will produce a good effect, for still better control of the illumination, it is of 90 advantage to use a reflecting screen that will give an astigmatic image of the light source as a semi-cylinder, or a semi-sphere with its center not at one of the light sources. With a semi-cylindrical mirror 45, Fig. 13, rays 95 from any point in the light source 47 out of focus, will follow both the lines 47, 48, 48, 49 and 47, 50, 50, 51. The effect of the reflections at 48 and 50 is to cause a concentrated light source to appear extended. 100 Owing to this effect, the proper placing of a concentrated light source relative to the small reflector 45, gives a result similar to that produced with an extended light source.

105 The extent to which the road and the sides of the road will be illuminated can be controlled by changing the distance back or in front of the focus at which the light source out of focus is placed. The intensity to which a particular part of the road is illuminated can be controlled by changing the intensity of the light source out of focus, from one place to another in its length, or if it is a concentrated source, its position relative to the reflector or mirror placed close to it, 110 either above or below.

115 In all the above combinations, a small screen 52, Fig. 8, may be placed in front of the lamp to prevent direct outward and upward radiation from the light sources.

120 The sources of light may be separate sources as 4 and 5, Fig. 1; or a continuous source extending in and out of the focus as at 4 and 15, Fig. 15. One source may be displaced from the focus, in front or behind 125

130

on the axis, as in Figs. 4 and 1; or it may be placed (see Figs. 15 and 16) in any position relative to said focus f , where rays from it will strike one half of the parabolic reflector as $3'$, Fig. 15, as if they had come from a point or points 17 in front of the plane 14 perpendicular to the axis through said focus; the other half of the reflector, as if they had come from point or points 18 10 behind said plane.

It is to be understood that the words "horizontal", "vertical", "upward", "downward", etc., are used throughout this specification and claims merely for convenience in 15 referring to relative locations and directions, and that my invention is not limited to headlights employed solely in the position herein described. Furthermore, such expressions as "axially displaced" does not exclude other 20 displacement or displacements, that is, the light source might be vertically or laterally displaced as well as axially displaced so far as the limitation "axially displaced" is concerned.

Obviously, by eliminating substantially that half of the reflector which reflects light upwardly one object of my invention, namely, that of adequately illuminating the roadway without producing upward glare, 30 is attained without employing means to shield one-half of the reflector from the light and without employing means to obstruct light after being reflected upwardly. In Fig. 1, for example, if substantially the upper half of the reflector is cut away or in any way rendered inoperative, the reflector 6 is not essential, although in the more specific aspect of the invention the reflector is important more completely to utilize the radiant light. Likewise in Fig. 3, if the lower 40 half of the deflector were eliminated the operation of the apparatus would be substantially the same as when employing the obstruction 10.

45 What I claim is:

1. Projection apparatus comprising a light source, a substantially paraboloidal reflector having its focus substantially in said light source for horizontally reflecting a concentrated beam of light a considerable distance along a roadway, a second light source, the second light source being long and narrow and being disposed along the axis of the reflector on one side of the focus, and a 50 deflector arranged to deflect light emanating from said second source to the near portions and sides of the roadway.

2. Projection apparatus comprising a

light source, a substantially paraboloidal reflector having its focus substantially in said 60 light source for horizontally reflecting a concentrated beam of light a considerable distance along a roadway, a second light source, the second light source being long and narrow and being disposed lengthwise 65 in the axis of said reflector on one side of the focus, a transparent container for said light sources, the container having a cylindrical portion surrounding said second source, and a cylindrical deflector mounted 70 on the cylindrical portions of said container so as to deflect light emanating from said second source to the near portions and sides of the roadway.

3. Projection apparatus comprising a 75 light source, a substantially paraboloidal reflector having its focus substantially in said light source for horizontally reflecting a concentrated beam of light a considerable distance along a roadway, a second light source, 80 the second light source being elongate and being disposed on one side of the focus substantially concentrically with the axis of said reflector, a transparent container for said light sources, the container having a 85 cylindrical portion concentric with said second light source, and a cylindrical deflector mounted on the cylindrical portion of said container concentric with said second light source so as to deflect the light emanating 90 from said second source to the near portions and sides of the roadway.

4. Projection apparatus comprising a light source, a substantially paraboloidal reflector having its focus substantially in the 95 light source for horizontally reflecting a concentrated beam of light a considerable distance along a roadway, a second light source displaced from the focus, a transparent container for said light source, the container having substantially a cylindrical portion, and a substantially cylindrical deflector surrounding a portion of the cylindrical portion of the container for deflecting light to the reflector in such manner as to be 100 reflected downwardly, whereby near, distant and intermediate portions of the roadway are illuminated without producing upward glare.

In testimony whereof I hereunto affix my 110 signature in presence of two witnesses.
